UNITED STATES PATENT OFFICE.

DAVID B. ASHMAN, OF BALTIMORE, MARYLAND, ASSIGNOR TO THE D. B. ASHMAN MACHINE COMPANY, OF BALTIMORE, MARYLAND, A CORPORATION OF MARYLAND.

MACHINE FOR PIERCING PLIES OF FABRICS.

1,361,664.

Specification of Letters Patent.

Patented Dec. 7, 1920.

Application filed February 20, 1919. Serial No. 278,163.

To all whom it may concern:

Be it known that I, DAVID B. ASHMAN, a citizen of the United States, residing at Baltimore, in the State of Maryland, have 5 invented certain new and useful Improvements in Machines for Piercing Plies of Fabrics, of which the following is a specification.

This invention relates to a machine for 10 piercing plies of fabric and is especially useful in the manufacture of certain garments but may be used for other purposes.

The object of the invention is to provide 15 a machine for the purpose stated that shall be simple in construction and operation; that may rapidly drill through a pile of fabric of considerable thickness; that may be adjusted for a greater or lesser stroke; that will permit of the use of drills of different sizes and which has provision for 20 guiding and directing the drill while it is being driven through the fabric layers.

With these, and other objects in view, the invention is illustrated in the accompanying 25 drawings wherein,—

Figure 1, shows the improved machine in front elevation.

Fig. 2, illustrates the same in side elevation.

Fig. 3, shows the same in sectional top plan,—as though viewed on the line 3—3 of Fig. 1.

Fig. 4, illustrates a cross-sectional detail through the machine as the same would appear if cut on the line 4—4 of Fig. 1.

Fig. 5, shows another cross-sectional detail,—the section being taken on the line 5—5 of Fig. 1.

Fig. 6, illustrates on an enlarged scale a 40 vertical sectional detail through the ends of the spring-actuated means for normally sustaining the parts in an elevated or retracted position.

Fig. 7, shows in perspective one of the 45 notched supporting blocks, and

Fig. 8, illustrates the lower end of the motor shaft and the drill clamping device thereon and also shows a pin device for holding the shaft against revolution while 50 the drill is being attached or detached.

Referring to the drawings the numeral 9, designates a flat base plate which may have any desired outline but preferably is rectangular in shape, and this base-plate is pro-

vided at opposite sides with vertically-extending sockets 10, in which the lower ends of vertical tubes 11, are secured. These tubes 11, extend upwardly from the base plate and have a parallel but spaced-apart relation. Each vertical tube is provided in 60 its diametrically-opposite sides with longitudinal slots 12, as shown in Figs. 2, 3, 4, and 6 of the drawings,—said slots extending between but not to the ends of said tubes. The upper ends of the slots form 65 an upper stop-shoulder 13, as best seen in Fig. 6.

A block or bar 14, extends crosswise of each tube 11, and has its ends extending through the slots in the opposite sides of 70 the tube so that the block may move vertically within the limits of the slots. The lower side of each block 14, is provided with a crosswise notch 15, which is centrally located in the tube and beneath the blocks, 75 each tube contains a stem 16, having an enlarged head 17, which latter fits the interior of the tube so as to freely slide vertically thereon. The upper end of the stem 16, seats in the bottom notch 15, of the 80 block 14, and thus prevents the block from endwise movement that would cause it to become displaced with respect to the slots.

On the interior, each tube 11, is provided with a coiled spring 18, whose upper end 85 encircles the lower portion of the stem 16, and seats under the head 17. These springs are sufficiently compressed, when in their normal distended condition, to sustain the weight of certain parts which are supported 90 by the projecting ends of the blocks 14, as will presently be explained. The springs therefore keep the stems and blocks pressed upwardly until the blocks seat against the 95 upper ends of the slots 12, as clearly shown in Fig. 6, of the drawing.

A movable frame 19, having tubular bearings 20, at opposite sides, is located between the two vertical tubes and said tubular bearings of the said frame slidably fit over the tubes so as to move vertically thereon. The tubes therefore serve as guides on which the frame may move vertically toward and from the base plate.

By reference to Figs. 1 and 6, of the drawings it will be seen that the tubular bearings 20, seat on the projecting ends of

the blocks 14, so that the frame 19, is yieldingly sustained indirectly by the springs 18.

The frame 19, carries a motor 21, with its shaft 22, extending vertically and centrally between the two guide tubes 11. This motor is electrically driven and is provided with current-supply wires 23 and 24, which lead to a switch 25; wires 26, and 27, that extend from the switch to a separable connector 28, and wires 29 and 30, between the connector and motor windings. These connections are provided so that by simply separating the connector 28, the two short wires 29 and 30, may be detached with the motor 15 when it is desired to remove the motor from the frame 19, for repairs or adjustment.

The lower end of the motor shaft 22, preferably has an enlargement 31, through which a hole 32, extends and the lower end of the 20 enlargement carries a clamping head 33, for engaging and carrying a tool such as a needle or drill 34. The hole 32, in the enlargement has a useful function during the operation of the clamping head 33, to attach 25 or detach a drill, as will presently be explained.

The base plate 9, is provided with a slot 35, shown in Figs. 4 and 5, of the drawings, which slot extends in a crosswise direction 30 and between the sockets 10. Immediately at the rear of said slot, the base is provided with a vertically-extending socket 36, through the side of which a set screw 37, passes, as can be seen in Fig. 1. A disk 38, 35 is seated on top of the socket 36, and is provided with a central depending stem that projects down into said socket so that the set screws 37, may bind against said disk-stem and hold the same against rotation.

40 The disk 38, is further provided with a plurality of guide perforations 39, each differing from the other in diameter, and these perforations by extending vertically through the disk, serve as guides for the needle or drill 34, during the vertical movement of the latter, as will presently be explained. By providing perforations 39, of different sizes, drills or needles 34, also of different sizes 45 may be employed and thereby broaden the scope of utility of the machine.

To operate the machine, the needle or drill while revolving, must be moved downwardly through the guide plate or disk 38, and projected through the slot 35, and below the 55 base of the machine. The means for effecting this vertical movement of the needle or drill will therefore now be explained; reference being made particularly to Figs. 1 and 2, of the drawing.

60 Each tubular bearing 20, of frame 19, is provided on its outer side with a lug 40, and each lug pivotally sustains an operating lever 41,—a pivot screw 42, serving to effect this connection.

65 The upper ends of the two levers 41, ex-

tend well above the motor and are connected by a handle 43, while the lower ends of said levers are provided with a slot 44.

In the present instance a cross-bar 45, extends horizontally between and connects the 70 rear edges of the levers 41, for purposes of rigidity, but this bar is not essential and may be dispensed with. When the cross-bar is employed I preferably provide the same with a central horizontal perforation 46, 75 which perforation may be made to register or align with the perforation 32, in the enlargement 31, on the end of the motor shaft. When these perforations are in register, a locking pin 47, may be passed through the 80 bar perforation and projected into the perforation 32, so as to lock the motor-shaft 22, from rotation during the operation of inserting or removing a drill or needle, as shown in Fig. 8, of the drawing.

85 The lower end of each lever 41, is pivotally connected by a pin or screw 48, to the upper end of a link-bar 49. Each link-bar has its lower end pivoted by a pin or screw 50, to a lug 51, on the outer side of the base 90 socket 10.

By grasping the handle 43, and swinging the upper ends of the levers 41, on the pivots 42, said levers and the links 49 will assume the position indicated by broken lines in 95 Fig. 2, and during this movement will cause the tubular bearings 20 to slide downwardly on the guide tubes 11, carrying the frame 19, and motor 21, with it so that the revolving shaft 22, and the drill 34, will also move 100 downwardly and project the drill or needle through and below the bottom of the base plate 9.

In practice the pile or thickness of fabric layers 52, is formed by superposing as many 105 layers of fabric as may be desired and the entire machine is seated on top of the pile with its drill or needle in register with a marked spot on the uppermost fabric layer where it is desired to make a piercing. The 110 motor may then be started, if not already running, and the levers 41, then swung down thereby driving the revolving drill or needle through the entire pile of fabric layers.

115 In practice I have found it desirable to provide a stop device so that the downward stroke of the frame 19, motor 21, and drill or needle may be adjustably limited according to the thickness of the combined fabric layers to be pierced.

To effect this adjustment of the stroke I provide a vertical stop bar 53, having a stop device or head 54, on its lower end and provided with screw-threads 55, at its upper end.

120 The threaded end of this stop bar screws through a lug 56, on the frame 19, and lock nuts 57 and 58, serve to lock the stop-bar in any desired position.

125 Obviously the stop-bar will move verti-

cally with the frame and motor and when these parts are moved downwardly until the stop-device or head 54, strikes the top of the base plate, further downward movement of those parts will be prevented.

Having described my invention, what I claim is,—

1. In a machine for piercing plural plies of cloth, the combination with a flat base having two spaced-apart tubular guides extending vertically therefrom and each tube having a longitudinal slot therein, of a frame having a tubular bearing sleeve at each end thereof which sleeves are slidable on the exterior of the tubular guides so as to sustain the frame in a horizontal position between the guides; springs in the tubes; means projecting through the tube-slots and sustaining the sleeves and frame; a motor carried by the frame between the tubes and a piercing-tool depending from the motor and revolved by the latter.

2. In a machine for piercing plural plies of cloth, the combination with a flat base, having two spaced-apart vertical guide-tubes, of a horizontal frame having its opposite end slidably engaging the guide-tubes; a motor carried by the frame and having its shaft extending vertically between the guide-tubes; a drill attached to the lower end of said motor-shaft and depending between the guide-tubes; a lever at each end of the horizontal frame and each lever being pivoted between its ends to

an end of the frame and a link connected to each lever below the frame and each link having its lower end pivotally sustained.

3. The combination with a base, of spaced-apart guides extending above the base; a horizontal frame having tubular bearings which slide on said guides; a piercing tool movable with the frame and normally having its piercing end above the base; two levers each being pivotally connected to a tubular bearing of the frame, two links each connecting an end of a lever and having its other end pivoted at a fixed point whereby the movement of the levers and links will cause the frame to move toward or from the base, and means sustained by each guide-tube for yieldingly supporting the horizontal frame.

4. The combination with a base, of spaced-apart tubular guides extending above the base and each guide having a longitudinal slot; a spring in each guide; a block supported on the spring and projecting through said slot; a frame between the guides and supported at opposite sides on said blocks; a piercing tool movable with the frame and normally having its piercing end above the base, and means for moving the frames against the action of the springs and toward the base for projecting the tool-end below the base.

In testimony whereof I affix my signature.

DAVID B. ASHMAN.
